UNITED STATES PATENT OFFICE

ALFRED J. JOHNSON, OF EAU CLAIRE, WISCONSIN

BORING MACHINE

Application filed May 24, 1929. Serial No. 365,593.

This invention relates to an improved boring machine adapted for such use as reboring and finishing engine bearings.

An object of the invention is to provide a boring machine adapted for reboring a plurality of alined bearings such, for example, as the usual crank shaft and cam shaft bearings, found in the usual crank case or frame of an internal combustion engine.

10 A further object is to provide a portable boring machine adapted to be mounted on an engine frame or crank case and having a supporting member whereon a boring bar is adjustably mounted so that it may be readily alined with the bearings, and a power device being adjustably supported upon one end of said supporting member and having means for operatively connecting it with the boring bar, whereby the latter may be power driven,

15 said power device being adapted to operate the boring bar at different speeds to facilitate and expedite the operation of reboring the bearings.

20 A further object is to provide a portable boring machine comprising parallel bars adapted to be secured to the face of the engine frame, a plurality of bridge members adapted to be adjustably secured to said bars, and a supporting member of very rugged construction being mounted on said bridge members and provided with means for adjustably supporting a boring bar, said supporting member being located to one side of the longitudinal centerline of the machine so as to provide ample clearance for removing and replacing the bearings, when necessary, while the boring machine is mounted on the engine, and whereby an unobstructed view of the 25 boring bar is obtained so that the mechanic may readily note the operation of the cutting tools.

Features of the invention reside in the means provided for alining the boring bar with the bearings; the means for supporting the boring bar; the means provided for connecting the boring bar with the power device and for alining the power device with the boring bar; the means for manually longitudinally moving the boring bar; and, in the

general construction of the machine as a whole.

Other objects of the invention will appear from the following description and accompanying drawings and will be pointed out in the annexed claims.

In the accompanying drawings, there has been disclosed a structure designed to carry out the various objects of the invention, but it is to be understood that the invention is not confined to the exact features shown as various changes may be made within the scope of the claims which follow.

In the drawings;

Figure 1 is a perspective view showing my improved machine with the power device removed therefrom;

Figure 2 is a side elevation of the machine;

Figure 3 is an enlarged sectional plan view on the line 3-3 of Figure 2, showing the means for controlling the feed of the boring bar;

Figure 4 is a vertical sectional view on the line 4-4 of Figure 2;

Figure 5 is an enlarged vertical sectional view on the line 5-5 of Figure 2;

Figure 6 is a vertical sectional view on the line 6-6 of Figure 3;

Figure 7 is a sectional plan view on the line 7-7 of Figure 6, showing the means for alining the power device with the boring bar;

Figure 8 is a detail sectional view on the line 8-8 of Figure 5, showing the driving means for the boring bar;

Figure 9 is a detail sectional view showing the universal connection provided between the boring bar and the power device;

Figure 10 is a vertical sectional view showing the apparatus mounted upon an engine frame and the means provided for relatively adjusting the boring bar with respect to the engine frame;

Figure 11 is a perspective view illustrating a portion of a crank case and showing the means for alining the boring bar with the bearings;

Figure 12 is a perspective view showing

one of the collars for alining the cutter bar with the bearings; and

Figure 13 illustrates a portion of an engine crank case showing a bearing secured therein.

The novel boring machine shown in this invention comprises a boring bar 2 having a plurality of sockets 3 therein adapted to receive cutting tools 4, shown in Figures 2 and 4. These tools are adjustably mounted in the boring bar so that they may be adjusted to the proper position to accurately bore the engine bearings to the right diameter. Means not shown, are provided for securing the tools 4 to the boring bar.

The boring bar 2 is suspended from a supporting member 5, adjustably mounted on spaced bridge members 6 by means of split hubs 7, preferably integrally formed with the brackets. Each bridge member is provided with base portions 8 having slots 9 adapted to receive bolts 11, the heads of which are here shown slidably mounted in T-shaped slots 12, provided in a pair of parallel bars 13, adapted to be secured to the bottom face 14 of an engine crank case or frame 15, when the latter is inverted, as shown in Figures 4 and 10. The parallel bars 13 are adjustably secured to the crank case by suitable bolts 16, shown in Figure 1. The threaded terminals of these bolts are adapted to be received in the usual threaded sockets 17, provided in the face 14 of the crank case, as shown in Figures 4 and 11.

The means for supporting the boring bar 2 on the member 5, consists of a plurality of brackets 18, each having a split hub 19 mounted on the supporting bar 5 and secured thereto in adjusted position by cap screws 21. Each bracket 18 further has a split hub 22 arranged at right angles to the bore of the hub 19, and these hubs are adapted to receive a plurality of shanks 23 each having a bearing 24 provided at its lower end adapted to rotatably receive the boring bar 2, as best shown in Figure 1.

To rebore the alined bearings in a crank case or engine block, particularly the crank shaft bearings, the two end bearings are usually removed from the crank case as shown in Figure 11, to facilitate alining the boring bar with the bearings. These bearings usually comprise a lower member 20 and a cap 25 apertured to receive studs 26, secured to the crank case 15 as shown in Figure 13. The caps of the intermediate bearings (not shown) are also removed from their complementary lower members, after which a pair of alining collars 27 are seated in the semi-cylindrical bearing seats 28 provided at the ends of the crank case. These alining collars 27 are adapted to snugly fit in the concaved seats 28, and each is provided with a bore 29 adapted to rotatably receive the boring bar 2, as shown in Figure 11. By thus supporting the boring bar 2 in the two alin-

ing collars 27, positioned one at each end of the crank case, the boring bar will be axially alined with the axis of the several bearings.

The parallel bars 13 may then be secured to the face 14 of the crank case, as shown in Figures 4 and 10, and the bridge members 6 positioned thereon, as best shown in Figures 1 and 10. The cap screws 30 mounted in the split hubs 22 of the brackets 18, and also the cap screws 21 in the hubs 19, are loosened to permit the shanks 23 to be adjusted with respect to the supporting member 5. The boring bar 2 is then inserted in the bearings 24, at the lower ends of the shanks 23, after which it is axially alined with the crank shaft bearings by means of the alining collars 27, fitted onto the end portions of the bar. When the boring bar has thus been alined, the bolts 21 in the hubs 19 are tightened to secure the brackets 18 to the supporting member 5 and, in like manner, the bolts 31 are tightened to secure the shanks 23 in position in the hubs 22, thereby rigidly supporting the boring bar a fixed distance from the supporting member 5. The alining collars 27 are then removed, and the end bearings 20-25 secured to their respective seats 28, as shown in Figures 2 and 13, after which the cutting tools 4 are mounted in the boring bar 2, as shown in Figures 2 and 4.

One of the features of this invention resides in the means provided for driving the boring bar 2. In machines of this character, the boring bar is usually manually rotated by a suitable crank, terminally secured to one end thereof, and the axial feeding of the bar is accomplished by the provision of suitable threads on one end of the boring bar adapted to be engaged with a suitable nut or member retained in fixed relation with respect to the crank case.

In the apparatus here shown, the boring bar 2 is driven by a power device adjustably supported upon one end of the supporting member 5, as shown in Figures 2 and 5.

This power device comprises a gear casing 31, including lower and upper sections 32 and 33, respectively, as shown in Figure 6. The lower section 32 is suitably secured to a bracket 34 adjustably secured to a split collar 35, provided with a clamping bolt 36, whereby it may be rigidly clamped to the supporting member 5, as shown in Figure 5. The collar 35 has an extension 37 provided with threaded sockets 38 adapted to receive cap screws 39, traversing slots 41 provided in the bracket 34, as shown in Figure 2. A motor 42 is also secured to the bracket 34, as shown in Figure 5, and has a belt 43 operatively connecting it with a grooved pulley 44, secured to one end of a sleeve 45 rotatably mounted in a bearing 46, provided in the gear casing 31, as shown in Figure 3. A pinion 47 is provided at the opposite end of

the sleeve 45 and meshes with a gear 48 connected with a pinion 49 by means of a hub 51. The gears 48 and 49 and hub 51 are rotatably mounted upon a stub shaft 52 non-rotatably supported in hubs 53 provided in the gear casing 31.

A gear wheel 54 meshes with the pinion 49 and is secured to a flanged shaft 55, having a pinion 56 terminally secured thereto which meshes with a gear 57 secured to a shaft 58 rotatably mounted in bearings 59 and 61 and having a worm 62 secured thereto. This worm meshes with a worm wheel 63 loosely mounted upon an upright feed shaft 64, rotatably mounted in bearings 65 and 66 provided in the lower section 32 of the gear casing 31, as best shown in Figure 8. Teeth 67 are cut in the periphery of the feed shaft 64 adjacent its lower end, adapted to mesh with a rack bar 68 secured to a sleeve 69, slidably, but non-rotatably mounted in a guide 71 provided in the gear casing 31, as shown in Figures 6 and 7. The above described train of gears provides the means for feeding the boring bar longitudinally during operation of the apparatus.

The means for rotating the boring bar is best shown in Figures 2 and 3, and comprises a shaft 72 rotatably mounted in a bearing 73 secured to the tubular guide 71, and an anti-friction bearing 74 provided in the gear wheel 54, as shown in Figure 3. The shaft 72 also traverses the sleeve 45 and is adapted for relative rotation with respect thereto. A clutch 76 is slidably but non-rotatably mounted upon the shaft 72 between the pinion 47 and the gear wheel 54, and is adapted to be selectively moved into and out of driving engagement with the clutch teeth 77 and 78 provided upon the pinion 47 and gear 54, respectively, as shown in Figure 3. A yoke 79 is operatively connected with the clutch 76 and has an operating lever 81 located exteriorly of the casing and projecting forwardly from therebeneath, as shown in Figures 3 and 6, whereby it may be conveniently manipulated by an operator stationed adjacent to the machine. In Figure 3, the clutch 76 is shown in neutral position, whereby the shaft 72 will be stationary.

A pinion 82 is terminally secured to the shaft 72 and meshes with a gear 83 mounted upon a drive shaft 84 rotatably mounted in bearings 85 and 86 provided on the tubular guide 71, as shown in Figure 2. The gear 83 is non-rotatably connected with the shaft 84 by means of a suitable feather key 87 secured to the bore of the gear and having a driving connection with the shaft 84 by means of a keyway 88. The drive shaft 84 has an enlarged portion 89 rotatably mounted in the sleeve 69 and retained therein by means of a collar 91, secured to the shaft 84, as shown in Figure 7. One end of the enlarged shaft portion 89 has an annular flange 92 adapted

to engage one end of the sleeve 69 and which cooperates with the collar 91 to prevent relative longitudinal movement of the shaft 89 with respect to the sleeve 69.

The means for operatively connecting the drive shaft 84 with the boring bar 2 is best shown in Figures 7 and 9, and comprises a link 93 provided with terminal balls 94 and 95, adapted to be received in sockets 96 and 97, respectively, as shown. The socket 96, it will be noted, is formed in the adjacent end of the boring bar 2 and the socket 97 is provided in the projecting portion 98 of the enlarged shaft portion 89 of the drive shaft 84. The exterior diameter of the projecting portion 98 corresponds to the diameter of the adjacent end of the boring bar 2.

The balls 94 and 95 are each provided with a drive pin 99 adapted to be received in slots 101 provided in the ends of the boring bar 2 and projecting shaft portion 98. The balls are retained in their respective sockets by means of suitable washers 102 and split retaining rings 103, seated in annular grooves 104 provided in the walls of the sockets 96 and 97, as shown in Figure 9. The link 93, balls 94 and 95, sockets 96 and 97, and the drive pins 99, when operatively connected provide, in effect, a universal joint between the boring bar and the drive shaft.

The means provided for axially alining the drive shaft with the boring bar, consists of a sleeve 105 slidably mounted upon the adjacent end of the boring bar 2, as shown in Figure 7. This sleeve is adapted to be fitted over the projecting portion 98 of the enlarged shaft portion 89 of the drive shaft 84. To aline the drive shaft with the boring bar, the power device is adjusted upon the supporting member 5 by means of the split collar 35 and cap screws 39, securing the collar 35 to the bracket 34 as shown in Figure 5. Before the cap screws 36 and 39 are tightened, the drive shaft 84 is axially alined with the boring bar 2 and the alining sleeve 105 longitudinally translated upon the boring bar until it is moved into engagement with the projecting portion 98 of the shaft 89, and the end thereof abuts against the annular flange 92, as shown in Figure 7. The cap screws 36 and 39 may then be tightened to rigidly secure the collar 35 to the supporting member 5, and the collar to the bracket 34, after which the machine is ready for operation.

It is to be understood that, before connecting the boring bar to the power device, the boring bar is alined with the bearings to be reborod or finished, and firmly supported in alinement therewith by means of the brackets 18, as hereinbefore described.

Means are provided for disengaging the worm wheel 63 from the feed shaft 64 to permit the drive shaft and boring bar to be manually moved longitudinally in the tubular guide 71. Such means is best shown in

Figure 8, and comprises a cap 106 secured to the upper reduced portion 107 of the feed shaft 64. This cap has a spring-actuated bolt 108 mounted therein, the lower end of which is adapted to be received in one of a plurality of sockets 109, provided in the adjacent face of the hub of the worm wheel 63. A finger grip 111 is secured to the upper end of the bolt 108 and has a depending lug 112 adapted to be moved into engagement with the upper face of the cap 106 to retain the bolt 108 out of engagement with the sockets 109. In Figure 8, the lug 112 is shown out of engagement with the upper end of the cap 106, thereby permitting the bolt 108 to engage one of the sockets 109. When thus positioned, the longitudinal feeding of the boring bar will be automatically accomplished by the power device, simultaneously as the boring bar is rotated. When the finger grip is elevated to the dotted line position, shown in Figure 8 and rotated substantially a half revolution to cause the lug 112 to engage the upper face of the cap 106, the lower end of the bolt 108 will be out of engagement with the sockets 109, thereby disengaging the feed shaft 64 from the worm wheel 63, and thus permitting the boring bar to be longitudinally moved by manually rotating the feed shaft 64.

In the operation of this apparatus, the supporting member 5 is mounted upon the lower face of the engine crank case, as shown in Figures 4 and 10, and the boring bar aligned with the bearings as hereinbefore described. The boring bar is then operatively connected to the drive shaft 84, as shown in Figure 7, and the power device firmly secured to the supporting member 5. The proper tools 4 may then be inserted in the sockets 3 in the boring bar and the clutch 76 moved into engagement with one or the other of the clutches 77 or 78, depending upon the speed at which it is desired to rotate the boring bar. If it is desired to rotate the boring bar at a slow rate of speed, the clutch 76 is moved into driving connection with the clutch teeth 78 and, on the other hand, if it is desired to rotate the boring bar at a relatively higher speed, the clutch is moved into driving connection with the clutch teeth 77, thereby connecting the shaft 72 directly with the grooved pulley 44 for direct rotation therewith. Power is transmitted from the shaft 72 to the drive shaft 84 through the gears 82 and 83.

The upright feed shaft 64 is adapted to rotate at a constant speed, regardless of the speed of rotation of the drive shaft 84. This will readily be understood as a result of its connection with the pulley 44 thru the pinion 47, gear 48, pinion 49, gear 54, pinion 56, gear 57, worm 62, and worm gear 63, the latter being adapted to be operatively connected

with the feed shaft 64 by the spring-actuated bolt 108.

The supporting member 5 provides an important feature of this invention in that it furnishes a rigid support for the boring bar 2. If necessary, several bridge members 6 may be employed, located between the brackets 18 supporting the boring bar. The supporting member 5 is of large diameter, as shown, and one end thereof overhangs one end of the apparatus, as shown in Figures 1 and 2, to provide a support for the power device which is mounted thereon. It will also be noted, by reference to Figure 1, that the power device constitutes a complete power unit, including the motor and the necessary mechanism for controlling the operation of the boring bar. The power device may be quickly detached from the apparatus by simply loosening the cap screws 36 and 39 and uncoupling the universal joint connecting the drive shaft with the boring bar. The cap 106 is preferably provided with a plurality of radial arms 113, whereby the feed shaft 64 may be manually rotated to longitudinally move the boring bar 2 during operation of the machine. Such manual operation of the boring bar may be conveniently accomplished when the bolt 108 is moved out of driving engagement with the sockets 109 in the hub of the worm gear 63. It will thus be seen that the apparatus is very flexible in operation and its construction is such that it may be utilized for boring practically all types and sizes of aligned engine bearings.

The novel mounting of the boring bar upon the supporting member 5 permits universal adjustment of the boring bar whereby it may be axially aligned with either the crank shaft or cam shaft bearings in the engine crank case, as shown by the full and dotted lines in Figure 10. It will also be noted, by reference to Figures 1 and 10, that the supporting member 5 is offset to one side of the longitudinal centerline of the crank case to provide ample clearance for adjusting the boring bar 2.

The two speed drives for the boring bar 2, provided by the clutch teeth 77 and 78, and the clutch 76, provides means whereby the cutting tools 4 may be operated at a speed most suitable for the particular class of work to be performed. The sturdy construction of the boring bar supporting means also prevents chattering of the tools and insures accuracy and high grade work, as well as increased production.

I claim as my invention:

1. In a portable machine for boring engine bearings, the combination of two or more bridge members adapted to be adjustably secured to the engine frame, a split hub on each bridge member, a supporting member secured in said hubs, brackets mounted on said supporting member, a boring bar,

means mounted in said brackets and adapted to rotatably support said boring bar, and a variable speed power device mounted at one end of said supporting member and having a universal driving connection with said boring bar, said power device also having means for automatically longitudinally feeding the boring bar.

2. In a portable machine for boring engine bearings, the combination of two or more bridge members adapted to be adjustably secured to the engine frame, a split hub on each bridge member, a supporting member secured in said hubs and having one end overhanging the engine frame, brackets mounted on said supporting member, a boring bar, means mounted in said brackets and adapted to rotatably support said boring bar, a power device demountably supported on the overhanging end of said supporting member and having means for operating said boring bar, and means on said power device operable to permit manual operation of said boring bar.

In witness whereof, I have hereunto set my
25 hand this 17th day of May 1929.

ALFRED J. JOHNSON.
